(57) CLAIM

The ornamental design for a wine case, as shown and described.

DESCRIPTION

FIG. 1 is an isometric view of a wine case showing my new design;

FIG. 2 is a top plan view thereof;

FIG. 3 is a front elevational view thereof, the rear elevation being a mirror image of the front;

FIG. 4 is a left side elevational view thereof, the right side being a mirror image of the left side;

FIG. 5 is a bottom plan view thereof;

FIG. 6 is a bottom plan view of the lid of the wine case;

FIG. 7 is an isometric view of the base of the wine case, with the lid removed;

FIG. 8 is a top plan view of the base of the wine case, with the lid removed;

FIG. 9 a front elevational view of the base of the wine case, with the lid removed;

FIG. 10 view is a left side elevational view of the base of the wine case, with the lid removed, the right side being a mirror image of the left side; and,

FIG. 11 is a rear elevational view of the base of the wine case, with the lid removed.

The lid and base are shown separately for clarity of illustration.
